WATERPROOF CIGARETTE CASE

Filed Oct. 17, 1921

WITNESS: *W. J. Dawson*
Thomas S. Tarpin

John G. Welsh.
INVENTOR
BY
Victor J. Evans
ATTORNEY

UNITED STATES PATENT OFFICE.

JOHN G. WELSH, OF YOUNGSTOWN, OHIO.

WATERPROOF CIGARETTE CASE.

Application filed October 17, 1921. Serial No. 508,103.

To all whom it may concern:

Be it known that I, JOHN G. WELSH, a citizen of the United States, residing at Youngstown, in the county of Mahoning and State of Ohio, have invented new and useful Improvements in Waterproof Cigarette Cases, of which the following is a specification.

The object of my said invention is the provision of a cigarette case, designed to be carried by swimmers and possessed of water excluding capacity and yet adapted to be expeditiously and easily opened for the removal of a cigarette and as readily closed.

To the attainment of the foregoing, the invention consists in the improvement as hereinafter described and definitely claimed.

In the accompanying drawings, forming part of this specification:—

Figure 1 is a vertical section taken through a cigarette case constructed in accordance with my invention.

Figure 2 is a cross section taken in the plane indicated by the line 2—2 of Figure 1.

Figure 3 is a detail view illustrating the cover of the case and the rod connected thereto.

Figure 4 is a detail view illustrating the adaptability of the said rod to be flexed.

Figure 5 is a detail view of the lighting device comprised in the improvement.

Similar numerals of reference designate corresponding parts in all of the views of the drawings.

The body 1 of my novel case is preferably made of aluminum, though it may be made of any other material compatible with its purpose.

The said body 1 is concavo-convex in cross section, Figure 2, to better fit the wrist of the user, and is provided on its longitudinal edges with loops 2 to receive elastic straps 2^x for fastening it on the wrist. The open end of the body 1 is surrounded by a beveled end 3, and on the said beveled end is a gasket 4, preferably of rubber. As indicated by 5 the body 1 is lined with cork which is preferably about one-sixteenth of an inch in thickness.

Appropriately fixed in the longitudinal center of the body 1 is a tube 6 which extends throughout the length of the said body, and in the said tube 6 is an apertured diaphragm 7, appropriately fixed to the tube.

In addition to the body 1 the case comprises a cover 8 which is lined with cork as

indicated by 9, this lining being preferably about one-eighth of an inch in thickness. The cover 8 is provided with a beveled flange 10 adapted to snugly fit the beveled end 3 of the body and also adapted to snugly fit over the rubber gasket 4 so as to render the case absolutely watertight.

Connected to or formed integral with the cover 8 is a rod section 11 centrally arranged and flexibly connected at 12 to a second rod section 13. The rod section 13 is guided and movable rectilinearly through the diaphragm 7 and is provided at the opposite side of said diaphragm to the cover 8 with an enlargement 14 which may be a nut or other device appropriately secured on the rod section 13. Surrounding the rod section 13 and interposed between the enlargement 14 and the diaphragm 7 is a spring 15, designed to strongly though yieldingly hold the cover 8 in its closed position, and also designed when the cover is opened and released to quickly draw or snap it back into closed position. The flexible or hinge connection 12 between the rod sections 11 and 13 permits the cover 8 to drop down over the side of the body 1 when the cover is withdrawn or opened to the greatest extent.

At 15 is a lighting device attached to the top of the cover 8 in a horizontal position on the outer side of the cover. The said lighting device may be of any desired construction, though I prefer, of course, to have it comprise a hollow body 16 and a removable member 17 which latter when placed in the body 16 as illustrated is designed to seal the said body 16 in a watertight manner.

It will be apparent from the foregoing that several cigarettes may be carried in my novel case in such manner that there is no liability of the cigarettes being injured or rendered useless through wetting while the case is fastened to the wrist of a party in swimming or bathing; and it will also be apparent when such party desires to use a cigarette it is simply necessary to withdraw the cover 8 against the action of the spring 15, remove a cigarette, and then release the cover 8 whereupon the said spring 15 will quickly return the cover 8 and yieldingly hold it in its closed position, with the result that water or moisture will be effectively excluded from the case.

I have entered into a detailed description of the construction and relative arrange-

ment of parts embraced in the present and preferred embodiment of my invention in order to impart a full, clear and exact understanding of the said embodiment. I do not desire, however, to be understood as confining myself to the said specific construction and relative arrangement of parts inasmuch as in the future practice of the invention various changes and modifications may be made such as fall within the scope of my invention as defined in my appended claims.

Having described my invention, what I claim and desire to secure by Letters-
15 Patent, is:—

1. A waterproof cigarette case comprising a hollow body lined with cork and open at one end and having such end beveled and equipped with a gasket, a longitudinal central tube fixed in the body and extending throughout the length thereof and having at an intermediate point a fixed and apertured diaphragm, a removable cover lined with cork and beveled to fit the beveled end of the body and shaped to snugly receive the gasket on the said end of the body, a rod section fixed to the center of the cover and normally disposed in the tube of the body, a second rod section hingedly connected to the first-named rod section and

movable rectilinearly in the said diaphragm and having an enlargement at the opposite side of the diaphragm with reference to the cover, and a coiled spring contained in the tube and surrounding the second-named rod section and interposed between the enlargement thereof and the diaphragm. 35

2. A waterproof cigarette case comprising a body open at one end, a removable cover, means for sealing the joint between the body and cover when the latter is in closed position, and yielding means within the body and connected with the cover for yieldingly holding the cover under pressure against the body. 40

3. A waterproof cigarette case comprising a body open at one end, a removable cover, means for sealing the joint between the body and cover when the latter is in closed position, and yielding means within the body and connected with the cover for yieldingly holding the cover under pressure against the body; the said yielding means including a rod connected to the cover and provided with an abutment, an abutment in the body, and a spring interposed between the two abutments. 50 55

In testimony whereof I affix my signature.

JOHN G. WELSH.
